Primary Examiner — Cynthia Ramirez*(74) Attorney, Agent, or Firm* — Luedeka Neely Group, P.C.(57) **CLAIM**

The ornamental design for a winch control handle, as shown and described.

DESCRIPTION

FIG. 1 is a front perspective view of a winch control handle showing our new design;

FIG. 2 is a top plan view thereof; and

FIG. 3 is a front elevation view thereof;

FIG. 4 is a rear elevation view thereof; and,

FIG. 5 is a right side elevation view thereof.

The broken lines in the figures show portions of the winch control handle, which form no part of the claimed design.

1 Claim, 5 Drawing Sheets(56)
